DEVICE FOR CONVERTING ELECTRIC OSCILLATIONS INTO MECHANICAL VIBRATIONS

Application filed May 18, 1927, Serial No. 192,430, and in the Netherlands May 21, 1926.

This invention refers to a device for converting electric oscillations into mechanical vibrations and more particularly for converting modulated electric currents into sound vibrations.

5 The invention has for its object to provide an improved construction of such a device by which the sensibility is increased and natural vibrations of the component members are substantially reduced.

10 When rectilinear mechanical vibrations are to be produced or in particular when it is desired to generate sound vibrations, the simplest and at the same time the most satisfactory transfer of the vibrations of the armature to the sound producing membrane is ensured when the movements of the armature as well as the sound producing membrane are performed as perfectly straight- 15 line motions.

According to the invention the armature is adapted to move rectilinearly between two parallel but oppositely directed permanent magnetic fields and in the direction of these 20 fields. The armature is secured to one or more laminated springs which support the armature between the permanent magnets and permit a sufficient rectilinear movement of the armature.

25 The invention will hereinafter be explained in greater detail by reference to the accompanying drawing which illustrates by way of example the invention adapted to a loud-speaker.

30 In the said drawing:

Figure 1 is a longitudinal section taken on the line I—I of Figure 2.

Figure 2 is a lateral view.

40 Figure 3 is a cross-sectional view taken on the line III—III of Figure 2.

The legs of a permanent horse-shoe magnet 1 have fixed to them four pole-shoes 2, 3, 4 and 5 in such a manner that 2 and 5, and 3 and 4 respectively have the same polarity 45 so that in the rather narrow gaps between 2 and 4 and between 3 and 5 respectively, oppositely directed fields are brought about.

Within these gaps a soft iron armature 6 is adapted to move but only in the direction 50 of the force lines. If this armature is mid-

way in the two said gaps it is evidently in unstable equilibrium as it is attracted with an equal force by the two pairs of poles 2, 3 and 4, 5 respectively. As soon, however, as a magneto-motoric force is applied within the 55 armature the equilibrium is broken and the armature is attracted either by 2 and 3 or by 4 and 5 depending on the direction of the said force. This magneto-motoric force results, for example, when the current flows 60 in the small coil 7. This coil 7 surrounds the armature 6 so as to allow a small amount of movement of the armature. The electric oscillations which are to be converted are passed thru coil 7. The straight-line reciprocating movements of the armature 6 are transferred by means of two small rods 8 and 15 a yoke 9 to a small rod 10 that acts on the membrane (cone or similar member). In order that the armature may always recede 70 from every position to the neutral position, the two ends of the armature are secured to the centres of two laminated springs 11. Either one or both ends of the spring are clamped by screws 12.

Owing to the fact that the members 6, 8, 9 and 10 all perform perfectly rectilinear reciprocating movements no forces of torsion are produced in them and therefore resonant influences due to the natural oscillations of these elements of the mechanism are avoided.

75 What we claim is:

1. A device for converting electrical oscillations into mechanical vibrations comprising a permanent magnet, pole pieces for said magnet providing two north poles and two south poles, a flat armature positioned between the poles of said pole pieces, said pole pieces being so constructed and arranged that there is one north pole and one south pole 80 below and above the armature, members connected to the ends of said armature, a yoke connecting said members, an operating rod connected to said yoke, and a coil surrounding said armature, said coil being adapted to 85 carry a voice-modulated current to vary the magnetic force between the magnet pole pieces and the armature.

2. A device of the character described comprising a frame, a magnet, an armature in 90

the field of the magnet, a coil around the armature, and two springs fastened at their ends to the frame, the ends of the armature being fastened to the centers of the springs.

5 3. A device according to claim 1, including in addition thereto two springs, the armature being fastened to the centers of the springs, and means for supporting the ends of said springs, said means being secured to said magnet.
